US0D1043200S

(12) **United States Design Patent** (10) Patent No.: **US D1,043,200 S**
(45) Date of Patent: ** Sep. 24, 2024

(54) **COAT RACK**

(71) Applicant: **Jie Wang**, Anji County (CN)

(72) Inventor: **Jie Wang**, Anji County (CN)

(**) Term: **15 Years**

(21) Appl. No.: **35/520,061**

(22) Filed: **Jan. 26, 2024**

(80) **Hague Agreement Data**

Int. Filing Date: **Jan. 26, 2024**

Int. Reg. No.: **DM/234980**

Int. Reg. Date: **Jan. 26, 2024**

Int. Reg. Pub. Date: **Feb. 16, 2024**
